SAFETY CONTAINER FOR VOLATILE LIQUIDS

Charles K. Huthsing, Jr., Libertyville, Ill.
(1685 Shermer Road, Northbrook, Ill. 60062)

Filed Jan. 29, 1970, Ser. No. 21,144

Term of patent 14 years

Int. Cl. D9—07

U.S. Cl. D9—175

FIG. 1 is a perspective view of a safety container for volatile liquids embodying my new design;

FIG. 2 is a side elevational view, the opposite side being a mirror image of the side shown;

FIG. 3 is a front elevational view;

FIG. 4 is a top plan view;

FIG. 5 is a rear elevational view; and

FIG. 6 is a bottom plan view thereof.

I claim:

The ornamental design for a safety container for volatile liquids, substantially as shown and described.
